W. GRAH

SIGNAL MEANS

Filed Dec. 1, 1924

Patented May 12, 1925.

1,537,080

UNITED STATES PATENT OFFICE.

WILLIAM GRAH, OF WATERVILLE, OHIO.

SIGNAL MEANS.

Application filed December 1, 1924. Serial No. 753,361.

To all whom it may concern:

Be it known that I, WILLIAM GRAH, a citizen of the United States, and a resident of Waterville, in the county of Lucas and State 5 of Ohio, have invented a new and useful Signal Means, which invention is fully set forth in the following specification.

This invention relates to signal devices, and particularly to a device of this character intended for use in connection with automobiles, and has for its object the provision of a simple, efficient and novel means of this character.

15 The invention is fully described in the following specification, and while in its broader aspect it is capable of embodiment in different forms, a preferred embodiment thereof is illustrated in the accompanying drawings, in which.—

20 Figure 1 is a fragmentary side elevation of an automobile with a signal device embodying the invention associated therewith. Fig. 2 is an enlarged section of the device taken on the line 2—2 in Fig. 1 with the signal member in inoperative position. Fig. 3 is a similar view with the signal member in operative position and with the pneumatic control means diagrammatically shown in connection therewith and partly broken away. Fig. 4 is an enlarged front elevation of the device with a part broken away, and Fig. 5 is a cross-section on the line 5—5 in Fig. 4.

Referring to the drawings, 1 designates a case or enclosure means adapted to be carried in convenient position on the side of an automobile or other vehicle body 2. This case is of vertically elongated form, is substantially rectangular in cross-section, and has a longitudinally extending slot or opening 3 in its outer side. A shaft 4 is journaled in the upper portion of the case 1 in transverse relation to the slot 3 and carries a pinion 5, which meshes with a rack bar 6, which is vertically disposed within the case and is guided at its upper end and retained in mesh with the pinion 5 by a guide 7 pivotally mounted on and projecting from the shaft 4. The lower end of the rack-bar 6 is connected to the upper movable end of a bellows 8 mounted in the lower portion of the case 1. Expanding movements of the bellows actuate the rack bar 6 to impart rotation in one direction to the shaft 4. The manual control means for the bellows 8 is shown, in the

present instance, as comprising a hand bulb 9, which may be mounted on the steering post of the associated vehicle, and a foot bulb 10, which may be disposed in convenient position to be operated by the driver. Each of these bulbs has suitable hose connection 11 with the bellows.

The shaft 4 has an arm 12 projecting transversely therefrom in position to swing through the case opening 3 when the shaft is rocked, and to this arm is attached one edge of a fan-like signal member 13. This member is of segmental form and has its inner edge attached to the rear of the case 1, as for instance to a bail member 14 attached to said case. The member 13 is foldable in the manner of a fan, and when the arm 12 is swung downwardly to a point within the case 1, the member is compactly folded within the case, and as the arm 12 swings outwardly and upwardly to operative horizontal position the signal member 13 unfolds and stands as indicated in Fig. 3. 65 70 75

It will be understood that upon forcing air into the bellows 8 it will be caused to expand and effect an upward movement of the rack bar 6, which in turn acts on the pinion 5 and turns the shaft 4 to throw the arm 12 and signal member 13 to project it to operative position. In order to facilitate a downward swinging of the arm 12 and member 13 the shaft 4 is provided with a spring 15, which exerts a turning movement on the shaft in the proper direction to return the signal member 2 to, and yielding-ly retain it in, inoperative position within the case. 85 90

Having thus described my invention, what I claim as new and desire to secure by Letters Patent is:

1. In a signal device of the class described, a case having an opening in the outer side thereof, a shaft, means yieldably urging rotation of said shaft in one direction, a pinion on the shaft, a rack in engagement with the pinion and movable lengthwise of the case, a bellows connected to the rack and operable to rock the shaft in one direction against the tension of said yielding means when the bellows is expanded, a fan-like signal member connected at one end to the shaft and at its other end to the interior of the case and operable to open up to signalling position outside the case through the opening therein when the shaft is rotated

by expansion of the bellows, and a hand bulb communicating with the bellows for operation thereof.

2. In a signal device of the class described, 5 a case having an opening in the outer side thereof, a shaft, means yieldingly urging rotation of said shaft in one direction, a pinion on the shaft, a rack in engagement with the pinion and movable lengthwise of the 10 case, a bellows connected to the rack and operable to rock the shaft in one direction against the tension of said yielding means when the bellows is expanded, a fan-like signal member connected at one end to the shaft

and at its other end to the interior of the 15 case and operable to open up to signalling position outside the case through the opening therein when the shaft is rotated by expansion of the bellows, a hand bulb communicating with the bellows for operation thereof, and a foot bulb also connected to operate said bellows having a spring for normally holding the foot bulb in extended position.

In testimony whereof I have hereunto 25 signed my name to this specification.

WILLIAM GRAH.
